UNITED STATES PATENT OFFICE.

FREDERICK W. TOEDT, OF HAMBURG, IOWA.

GAS-ENGINE.

SPECIFICATION forming part of Letters Patent No. 650,549, dated May 29, 1900.

Application filed January 30, 1899. Serial No. 703,920. (No model.)

To all whom it may concern:

Be it known that I, FREDERICK W. TOEDT, a citizen of the United States, residing at Hamburg, in the county of Fremont and State of Iowa, have invented new and useful Improvements in Gas-Engines, of which the following is a specification.

This invention relates to certain new and useful improvements in gas-engines; and it consists in the construction and organization of the parts thereof whereby I provide means for supplying the gas into serpentine gas-chambers in the cylinder-heads, in which chambers the gas is exploded to actuate the piston-head, which piston-head in its movement opposite to that which it is forced by the explosion ejects the spent product out of the cylinder, means also being provided for forcing the gas into the cylinder-heads, as will be hereinafter set forth.

In the drawings, Figure 1 is a sectional view taken through the main cylinder and through the exhaust and pump cylinder. Fig. 2 is an end elevation, the rods attached to the piston-heads being shown in section. Fig. 3 is a detail sectional view of a chamber having valves and openings, the same being interposed between the cylinder-heads of the main cylinder and the pump-cylinder. Fig. 4 is a vertical sectional view through one of the cylinder-heads, and Fig. 5 is a sectional view of a modified form of one of the cylinder-heads.

The main cylinder is surrounded by a wa-
35 ter-chamber *a*, and to the ends of said cylin-
der are attached heads *B*, which have therein
serpentine gas-chambers *b*, which open or lead
into the cylinder and through the outer edges
of the heads of the cylinder, and connected
40 with the gas-chambers *b* are chambers *E*. The
gas is exploded in these serpentine or elongated
chambers, the expansion of which ac-
tuates the piston. Through the center of the
cylinder-heads there are central openings *b'*
45 for the escape of the products of the exploded
gas, and through one of these openings the
piston-rod *b* is passed, the pipes connected
to the opening having a stuffing-box, through
which the piston-rod passes.

50 Adjacent to the cylinder *A* is suitably sup-
ported a pump-cylinder *C*, and to the heads
of said cylinders are attached coiled pipes or

tubes *D*, which have branch or oil-feed pipes *d*. The pipes *D* lead into chambers *E*, which are attached to the cylinder-heads, so as to 55 communicate with the serpentine chambers *b* therein. The chambers *E* are provided with check-valves *e e'*, and between the valves there is a gas-inlet opening *e²*, and to this opening one end of the coiled pipe *D* is con- 60 nected, and below or to one side of the opening *e²*, so as to be below the valve-seat *e'*, there is an opening *e³*, through which air and gas or other suitable explosive mixture may be admitted to the casing. 65

Gas, either natural or manufactured, is supplied to the pump-cylinder *C* through a suitable pipe, and the amount of such gas is regulated by a suitable valve and passes through openings *c*, which are positioned at 70 a suitable distance from the heads of the pump-cylinder, these openings being surrounded by ways or ducts *c'*, which communicate with each other by way of a pipe *C'*, which has two branches and a centrally-po- 75 sitioned regulating-valve *c³*, which may cut off the gas-supply pipe *c²*.

To the central or exhaust openings *b'* in the heads of the cylinder *A* are attached pipes or ways *F F'*, each having suitable con- 80 nections which open into an exhaust-cylinder *G* through the heads thereof, said cylinder having exhaust ports or openings *g*, which are centrally located and are surrounded by a way *g'*, which connects with the exhaust- 85 pipe *G'*.

The piston of the cylinder *A* and the pis-
ton of the pump-cylinder are both connected
so as to have the same stroke, and to attain
this end the piston-rods may be coupled to- 90
gether.

The valve in the exhaust-cylinder *G* is in-
tended to be moved from one side of the ex-
haust-openings *g* to the other side, and to ac-
complish such movement at the proper time 95
the valve-rod is coupled to an eccentric. Any
suitable means may be provided for igniting
the gas in the serpentine chambers in the
cylinder-heads *B*; but in practice I prefer to
use electric igniters for this purpose. 100

The construction of this type of gas-engine
has in view to provide for a circulation of
water around the main cylinder for the pur-
pose of keeping said cylinder cool, while the

maximum amount of heat will be absorbed by the cylinder-heads, and is utilized to expand or vaporize the explosive medium which is forced into the serpentine chambers there-
 5 in, and the explosive medium may be either natural or artificial gas, with or without the addition of a vapor from a hydrocarbon oil.
 In operation the pipe c^2 is connected with a gas-supply, the gas being either natural or
 10 artificial, and the reciprocation of the pump-piston draws the gas through the openings c from the supply-pipe, and after the piston passes one of the series of openings c the gas is forced through the coil D and into the
 15 valved mixing-chamber E . The gas which passes into the coil D may be enriched by letting into the coil oil, which is fed thereto through a pipe d . The oil-feed pipe d is connected with an oil-supply in any suitable
 20 manner, and said pipe may have a check-valve of any suitable construction. To vaporize the oil which is let into the coil D , said coil is kept heated by a lamp or gas-jet or in any
 25 suitable manner, and it is obvious that the temperature of the gas which is forced into the coil is raised as it is forced therethrough. The explosive mixture, consisting of gas enriched by a vapor from a hydrocarbon oil, is forced into the valved chamber E , where it is
 30 further mixed, and from thence to the serpentine passage in the cylinder-head, where it is compressed by the action of the piston in the main cylinder until the piston therein moves near enough to the cylinder-head to
 35 cause the usual igniting device to be brought into operative position. The gas in the serpentine passage in the cylinder-head is acted on by being mechanically compressed by the piston and by being expanded by the absorption
 40 of heat from the head of the cylinder. The serpentine passage serves as a chamber in which the gas is mixed before being exploded. The explosion drives the piston-head to the
 45 opposite end of the cylinder, and during said movement the piston in the pump-cylinder moves in the same direction. A back flow of the residue or products of combustion is prevented by the check-valve e , and the products of combustion escape from the cylinder
 50 through the central openings in the cylinder-head, passing therefrom through the pipes into the cylinder G , the valve in the cylinder G being attached to the eccentric, so that its movements will be such as to have the ports in
 55 the escape-cylinder open during the movement of the main piston toward the end of the

cylinder from which the spent gases are ejected and closed while the explosive force is acting upon the main piston. To form a proper explosive mixture, the regulating-valve c^3 is set so that the pump-piston when moved in one direction will draw through the pipes and the openings c the desired amount of gas, and at the same time will also draw air through the pipe D ; the air entering the lower section of the valved chamber E through the opening e^3 , the valve e being lifted by the suction produced by the pump-piston. At the same time that the air enters the opposite end of the pump-piston from where the gas is drawn into the same oil may be fed into one of the feed-pipes D through the oil-feed pipe carried thereby. It will be obvious that the explosive mixture is formed in the pump-cylinder at one stroke thereof, so that on the next stroke it will be forced through the pipe D into the valved chamber E , lifting the valve e thereof, and enters the cylinder through the serpentine passage in the cylinder-head.

Having thus described my invention, what I claim as new, and desire to secure by Letters Patent, is—

1. The combination in a gas-engine constructed substantially as shown and provided with cylinder-heads having serpentine chambers therein, of valved mixing-chambers E connected to the cylinder-heads, each chamber having a gas-inlet opening e^2 between the valves therein and an air-inlet opening e^3 below one of the valves substantially as shown and for the purpose set forth.

2. In a gas-engine, the combination with a main cylinder having heads with serpentine chambers therein, valved chambers E with openings, one of said openings being connected with the serpentine chambers in the cylinder-heads, coiled pipes D having oil-inlet pipes d , said coiled pipes being connected to the valved chambers E and to the heads of a pump-cylinder, the pump-cylinder having gas-supply openings c near each end and a pipe C connected with said openings, substantially as shown and for the purpose set forth.

In testimony whereof I have hereunto set my hand in presence of two subscribing witnesses.

FREDERICK W. TOEDT.
